[57] CLAIM

The ornamental design for a set of knives in a holder having a mouse motif, as shown and described.

DESCRIPTION

FIG. 1 is a front, perspective view of the set of knives in a holder having a mouse motif in accordance with the present invention, with the rear view being mirror image thereof;

FIG. 2 is a bottom plan view of the set of knives in a holder having a mouse motif shown in FIG. 1;

FIG. 3 is a top plan view of the set of knives in a holder having a mouse motif shown in FIGS. 1-2;

FIG. 4 is a top perspective view of one of the knives removed from the set of knives in a holder having a mouse motif, shown separately for ease of illustration; and,

FIG. 5 is a bottom perspective view of one of the knives removed from the set of knives in a holder having a mouse motif, shown separately for ease of illustration.
